REINFORCED CONCRETE FLOOR
CONSTRUCTIONWilliam J. Kupec and Albert W. Rawlins,
New York, N. Y.

Application November 22, 1941, Serial No. 420,048

2 Claims.

(Cl. 72—66)

This invention relates to a reinforced concrete floor construction which may be built rapidly, economically, and without utilization of the vast, costly and objectionable supporting formwork normally resorted to; and resulting in a floor of superior strength, reduced bulk, and improved merits.

Other objects and advantages will hereinafter appear.

In the accompanying drawings,

Fig. 1 is a perspective view of the reinforced concrete floor constituting the invention, the same being shown fragmentary, partially in transverse cross-section, various parts thereof broken away, and as it appears during construction, for clearness of illustration.

Figs. 2, 3, and 4 are transverse-sectional views showing different constructions of floors, with the utilization of the principles of the invention.

Figs. 5 and 6 are perspective views showing details of the invention.

Fig. 7 is a general fragmentary perspective view showing a modification of a reinforced concrete floor of the invention, the type of illustration being similar to that shown in Fig. 1.

Fig. 8 and Fig. 9 are respectively a plan view and a front elevation of a filler block, forming part of the modification of the invention shown in Fig. 7.

Fig. 10 is a general fragmentary perspective view, similar in character to that of Fig. 1, showing other details of the invention.

Fig. 11 illustrates another detail of the invention.

In the construction of the floor 1, Fig. 1, there is utilized a series of trusses 2 comprising top chords 3, bottom chords 4, strut-rods 5, and near to each end of each truss there is provided a plurality of vertical posts 6, which serve to thereat increase the shearing strength of the truss, as will be hereinafter seen. To the underside of the bottom chords 4 of each of the trusses 2 is secured a plurality of spacing bars 7, Figs. 1, 5, preferably by means of welds 8. Said trusses are securely connected to each other laterally by means of a series of horizontal rails 9, Figs. 1 and 6, each of which is provided with a plurality of predeterminately spaced holes 10, through which pass bolts 11 that serve to secure the rails 9 to the upper sides of the top chords 3 of the struts 2.

In constructing the floor 1, the trusses 2 are first properly positioned upon their supports, and are appropriately spaced laterally by aligning their top chords 3 with the holes in the rails 9, whereupon said rails and trusses are secured to

each other by the bolts 11 and nuts 12. There is then secured to each truss 2 a soffit-board 13 by means of placing it against the bottom edges 1a of its spacing bars 7 and passing bolts 14 through said boards and between the bottom chords 4 of the truss, and then tightening said bolts with nuts 15, to thereby effect a rigid engagement of the board with said spacing bars, in the manner illustrated in Fig. 5. Filler-blocks 16 are then placed in supported position upon the marginal shoulders 13a of soffit-boards 13, with their sides 16a bearing against and guided laterally by the terminal edges 1b of the spacing bars 7. Concrete 17 is then poured over the aforesaid structure, to fill the spaces between the sides 16a of filler-blocks 16 and over the soffit-boards 13, to encase the trusses 2, and to rise over and above the filler-blocks 16 to a plane level with the topmost edges 9a of the rails 9, thereby forming slabs 18 the concrete of which upon drying becomes an integral part of beams 19 taking the place of the aforesaid spaces and completely encasing their reinforcing trusses 2. Upon completion of the pouring of the concrete, the topmost edges 9a of rails 9 are utilized for screeding the top level of the concrete floor. When the setting of the concrete 17 is completed, the soffit-boards 13 are readily removed by merely unscrewing the bolts 14, leaving a finished floor 1 consisting of the slabs 18 integral with the reinforced beams 19, and bonded with the filler-blocks 16, the undersurfaces of which and those of the beams constitute the flush ceiling.

The trusses 2 are built of sufficient strength to carry the liquid concrete, the filler-blocks 16, soffit-boards 13, and the impact loads of the concrete buggies or wheelbarrows used in placing the liquid concrete, and together with the utilization of the above described method of constructing the floor 1 any temporary supporting form-work for the floor may be wholly or almost wholly dispensed with. It will be noted that shearing stresses upon the trusses 2 are actually greater during said work with the concrete and before setting thereof than they are when sustaining the floor loads which are thereafter carried by the finished floor-slab, and these intermediate additional shearing stresses are overcome by the vertical posts 6 forming part of the end portions of the trusses. It will be further seen that the trusses 2 are additionally strengthened against lateral deviation or buckling, by the transverse rails 9 to which they are secured, which besides exercising this function also serve for conveniently and accurately spacing and positioning the

trusses, for indicating precisely the level to which the concrete slab is to be poured, and finally for screeding the finished concrete floor surface with aid of their topmost edges 9a. It will be evident that during the construction and prior to the setting of the concrete, the welded spacing bars 7 together with the tightened bolts 14 provide a firm and accurate securing and horizontal alignment of the soffit-boards 13, relatively to the trusses 2, and these spacing bars 7 positively prevent any turning deviation or dislocation of the boards 13 laterally about the trusses from the correct horizontal and level positions of the soffit-boards, thereby resulting in accurately cast floor beams 19.

Each of the filler-blocks 16, Figs. 1, 8 and 9, is made hollow and light, as shown, and provided with one closed wall 16b and grooves 16c in its side-walls 16a to serve the purpose of convenient hand-holds and to produce a more effective bond between the block and the concrete of the beams

19. The blocks 16 are prefabricated of concrete, using as an aggregate a light weight material, as cinders, and they are produced to possess the same strength as the beams 19 and slabs 18 of the floor system. When therefore the latter with said blocks bond together firmly, they constitute a strong unitary floor body of superlative merits and economy, since much of it is thus prefabricated and the method permits reduction of weight and material requisite for said beams and floor slabs.

Due to the identical degrees of strength of the blocks 16 and the set concrete of the beams 19, taken together with their firm bond, aided by grooves 16c, the usual top floor slab 18 may be entirely dispensed with, as illustrated in Figs. 4 and 7, wherein the concrete of beams 19 follow and bond with the upper chamfered corners 16d of the blocks and extends to the level of the top surfaces 16e of the blocks. The latter therefore serve for screeding the top surface 19a of this concrete, and together with it constitute the top surface of the floor. In this modification, the trusses 2 are shown imbedded entirely below the top surfaces 19a, 16a of the floor, and for the same reason the transverse connecting rails 9 are secured to the undersides of the top cords 3 of the trusses. These rails are located in spaces 20 formed by separation of pairs of blocks 16, the bottoms of which spaces are closed by blocks 21 for supporting the concrete prior to the setting thereof.

In the construction of a floor of the modification of Figs. 4 and 7, it is rendered possible to instal and efficiently secure the wooden sleepers for the wooden flooring, as illustrated in Fig. 10, because it is possible to walk over and work upon the top surfaces 16e of the filler blocks immediately after the pouring of the concrete. For this purpose, therefore, the sleepers 22 are provided with down-hanging projections, such as bolts 23, which may extend into the spaces to be occupied by the beams 19, and soon after the pouring of the concrete may be appropriately positioned as shown, so that the bolts 23 become cast within the concrete and thereby readily and efficiently secure the sleepers in place, ready to receive the required wooden flooring 24.

When the blocks 16 are laid end to end, Figs.

1 and 11, upon the shoulders of the soffit-boards 13, the last block 16f of the series is so positioned that its rear wall 16b bears against the wall 25 of the building, in which manner any leakage of the concrete slab 18 while in fluid state is prevented into the hollow chamber 16g of block 16. It will be noted that in both floors, Figs. 1 and 7, the rear walls 16b of all the blocks 16 constitute a system of ribs extending transversely of struts 2, as close integrated concrete webs, thereby adding much strength to and greatly stiffening up the entire floor, being of particular value to resist wind or earth disturbances.

Fig. 2 shows a regular transverse-sectional view of the reinforced concrete floor of Fig. 1, to complete the illustration adequately, and Fig. 3 is a similar type view illustrating the principles of the method of the invention in connection with utilizing filler blocks 26 made of sheet steel forms 27, with or without steel ceiling lath 28 attached thereto.

Having thus described our invention, we claim:

1. In a reinforced concrete floor construction, a series of parallel trusses, each of which includes a pair of top chords and a pair of bottom chords, a plurality of horizontal spacing bars welded to and across the undersides of the bottom chords of each of said trusses and projecting laterally beyond each side thereof, a soffit-board disposed beneath each truss and against its spacing bars with side-portions of said soffit-board projecting beyond the ends of said bars, bolts extending through said soffit-boards and between the lower chords of said trusses and removably securing said soffit-boards in rigid engagement with said spacing bars, filler-blocks arranged between each pair of trusses with the bottom end portions of said filler-blocks resting upon the side-portions of said soffit-boards and with the ends of said filler-blocks spaced apart from said trusses by the spacing bars, and concrete in the spaces between said filler-blocks and around said trusses and above said soffit-boards.

2. In a reinforced concrete floor construction, a series of parallel trusses each of which includes a pair of top chords and a pair of bottom chords, rails resting on and extending across and bolted to the top chords of said trusses, a plurality of horizontal spacing bars welded to and across the undersides of the bottom chords of each of said trusses and projecting laterally beyond each side thereof, soffit-boards disposed beneath each truss and against its spacing bars with side-portions of said soffit-boards projecting beyond the ends of said bars, bolts extending through said soffit-boards and between the lower chords of said trusses and removably securing said soffit-boards in rigid engagement with said spacing bars, filler-blocks arranged between each pair of trusses with the bottom end portions of said filler-blocks resting upon the side portions of said soffit-boards and with the ends of said filler-blocks spaced apart from said trusses by the said spacing bars, and concrete covering said filler-blocks and filling the spaces between them and around said trusses and above said soffit-boards, the top surface of said concrete being screeded level with the tops of said rails.

WILLIAM J. KUPEC.
